UNITED STATES PATENT OFFICE.

CURTIS HUSSEY VEEDER, OF HARTFORD, CONNECTICUT.

DESIGN FOR A SPOKE-PIN.

SPECIFICATION forming part of Design No. 27,246, dated June 22, 1897.

Application filed May 7, 1897. Serial No. 635,592. Term of patent 14 years.

To all whom it may concern:

Be it known that I, CURTIS HUSSEY VEEDER, a citizen of the United States, residing in the city and county of Hartford, in the State of Connecticut, have invented a certain new and original Design for Spoke-Pins, of which the following is a specification, reference being had to the accompanying drawings, forming a part hereof.

My invention relates to a design for spoke-pins such as are secured to the spokes of bicycle-wheels for the purpose of actuating cyclometers; and it consists in a spoke-pin having the shape and configuration substantially as shown in the accompanying drawings, in which—

Figure 1 is an elevation showing one side of a spoke-pin which embodies my design. Fig. 2 is an edge view of the same as seen from the right in Fig. 1. Fig. 3 is an elevation showing the reverse side of the same, and Fig. 4 is an edge view of the same as seen from the bottom in Fig. 1.

As will be seen by reference to the draw-

ings, the outline of the body of the pin is substantially a parallelogram with rounded ends and a rounded projection at about the middle of one side. There are apertures *a a* in the rounded end portions of the parallelogram, and in one side of the body is a depression *b*, extending transversely across the body to the base of the projection *c*, and upon the opposite side of the body is a corresponding rib or ridge *d*. The projection *c* is slightly offset from the plane of the main portion *e* of the body, and a projection *f* is substantially vertical to the face of the projection *c*.

What I claim, and desire to secure by Letters Patent, is—

The design for a spoke-pin, substantially as shown and described.

This specification signed and witnessed this 5th day of May, A. D. 1897.

CURTIS HUSSEY VEEDER.

In presence of—

ETHEL L. WILLIAMS,
GEORGE R. HALL.
